(74) Attorney, Agent, or Firm—Altera Law Gorup, LLC

(57) **CLAIM**

The ornamental design for a headset, as shown and described.

DESCRIPTION

FIG. 1 is a perspective view of a headset showing my new design.

FIG. 2 is a front elevational view thereof.

FIG. 3 is a side elevational view thereof.

FIG. 4 is a top plan view thereof.

FIG. 5 is a bottom plan view thereof.

FIG. 6 is a view from the back thereof; and,

FIG. 7 is a side elevational view thereof.

The broken lines form no part of the claimed design.
